UNITED STATES PATENT OFFICE.

JOHN T. COLLINS, OF HARTFORD, CONNECTICUT, ASSIGNOR TO THE MERROW MACHINE COMPANY, OF SAME PLACE.

OVEREDGE SEWING-MACHINE.

SPECIFICATION forming part of Letters Patent No. 591,383, dated October 12, 1897.

Application filed May 20, 1897. Serial No. 637,419. (No model.)

To all whom it may concern:

Be it known that I, JOHN T. COLLINS, a citizen of the United States, residing in the city and county of Hartford and State of Connecticut, have invented certain new and useful Improvements in Overseaming-Machines; and I do hereby declare the following to be a full, clear, and exact description of the same, reference being had to the accompanying drawings, forming a part of this specification, and to the figures and letters of reference marked thereon.

My improvements relate to overseaming-machines, my object being to produce a new variety of overseam or edge finish made from three threads; and this invention consists in new forms of devices and new combinations of devices and mechanism for producing said new overseam or finish.

Figure 1 is a front-elevation of the machine. Fig. 2 is a left-hand elevation of the lower part of the machine, the door being removed to display the interior. Fig. 3 is a top view of the left-hand portion of the machine with work-plate removed to display the interior. Figs. 4, 5, 6, 7, 8, and 9 are diagrammatical views illustrating various stages of the stitch-forming operations. Fig. 10 is an enlarged sectional top view of a portion of the second-thread looper.

Throughout the drawings forming a part of this specification similar letters and figures of reference indicate like parts.

A indicates the frame of the machine; B, the main shaft; C, the eccentric; D, the driving-pulley; E, the eccentric connection; F, the needle-lever; G, the needle-bar; H, the needle, and I the presser-foot.

The lower grooved cam a is attached to the main shaft B, and is provided with a gear a' , which meshes into a gear a'' , attached to the upper grooved cam a^3 , which is operatively supported upon the upper shaft a^4 in such a manner that both of the said grooved cams rotate together, causing the reciprocation and oscillation of the looper-carrier b , which is operatively supported upon the sliding block b' , which is adapted to reciprocate in a dovetail groove formed by gibbs $b^3 b^4$, secured to the cap or door b^5 .

All of the parts hereinabove specifically in-

dicated by letters of reference are similar in form and construction to corresponding parts more completely described in Patents Nos. 414,234 and 441,315.

55

The base of the machine is indicated at 4. 18 indicates the work-plate. 19 indicates the swinging cap for the opening through the work-plate, which is made for convenient observation of the loop-forming process while adjusting the parts. 20 is the door covering the left end of the machine; 21, the feed-dog, with an opening for the passage of the loop-carrier 1; 22, the feed-carrier; 23, the feed-lever; 24, the feed-eccentric connection, and 65 25 the feed eccentric. Two thread-carrying looping instruments in addition to the needle are employed in this machine, the one, 9, being adjustably attached to and carried by the oscillating reciprocating looper-carrier b , controlled by the grooves in cams $a a^3$, while the other looper 1 is adjustably attached to a carrier 30, pivotally mounted upon a fixed stud or pin 31 and provided with an adjustable arm or pin 32, whose spherical head is received in a socket formed in one end of link 33, the opposite end of said link embracing a spherical crank-pin 34 on the main shaft B. 75

The path of looper 9 and the extent of its movement both above and below the work-plate are determined by the forms of the two controlling cam-grooves. Its movements are performed in a plane parallel with the needle, or substantially so, while the looper 1 is given a substantially uniform reciprocating 85 motion in a direction transverse to the axis of the needle, its path lying diagonal to the plane of the other looper's movement, so as to extend from on the rear side of the needle's line of motion to the front side of the 90 line of motion of the looper 9, as indicated in Fig. 2.

The looper 1 is provided with a point 10, adapted to enter between the side of the vertical needle and the thread carried thereby, 95 and said looper is also provided with two eyes $1^a 1^b$ and a groove 1^c for carrying, conducting, and protecting the thread, which I shall call the "second" thread, the "first" thread being considered that one carried 100 by the vertical needle. The second-thread looper 1 is also provided with a slabbing or

recess 12 to facilitate the passage of the point of the looper 9 between the side of the second-thread looper and the thread carried thereby, as will be further explained, and its operating portion is slightly inclined to the horizontal, the point being the more elevated.

- The looper 9 is provided with an eye 13 for carrying the third thread, the said eye being preferably countersunk and provided with 10 the usual grooves to facilitate the passage of the third thread, and it is preferably slabbed, as indicated at 14, Figs. 2 and 3, for the passage of the vertical needle H between the side of the said looper and its thread above 15 the fabric. The point 15 of the looper 9 is curved upward and forward or toward the second-thread looper 1 for the purpose of entering between the side of the latter and the thread carried thereby.
- 20 In order to explain the operations of the machine, it may be supposed that its motion has been arrested at a stage in the operation when the vertical needle is at or near its lowest point, at which time the needle, the 25 two loopers and threads will be in relative positions, approximately, as illustrated in Fig. 4.

Upon starting up the machine the looper 1 advances toward the needle while the latter 30 is rising, the point of said looper passing between the said needle and the thread carried thereby, while the looper 9 moves downward to carry its point below the line of travel of the looper 1, as illustrated in Fig. 5. As the 35 needle continues its upward movement the second-thread looper 1 continues through the loop of needle-thread, carrying its thread doubled through the loop of needle-thread to a point beyond the edge of the fabric, while 40 the third-thread looper 9 is moving to the position illustrated in Fig. 6. As the needle rises farther the third-thread looper 9 also rises, projecting its curved point between the second-thread looper 1 and the thread carried 45 thereby, as shown in Fig. 7. The needle rising still farther, the second-thread looper 1 withdraws, while the third-thread looper 9 advances, carrying its thread doubled through the loop of second thread and beyond the path 50 of the needle. In so doing the loop of second thread is raised above the edge of the fabric, but held back by said fabric and by the outer edge of the finger 16, as illustrated in Fig. 8. The second-thread looper continues to withdraw, 55 the needle descends, passing down between the side of the third-thread looper 9 and the thread carried thereby, while the said third-thread looper is retracting, as shown in Fig. 9. The needle continues its downward 60 movement through the fabric, the third-thread looper withdraws, leaving its thread passing doubled through loop of second thread and around the needle, completing one full cycle of operations in forming stitches 65 around the edge of the fabric. It will be observed that as the needle rises out of the fabric its thread is held below by the second-

thread looper, as shown in Fig. 6, and that in the completed stitches the needle-thread or first thread extends doubled through a loop 70 of third thread and the fabric, that the second thread extends doubled through a loop of first thread below the fabric, and that the third thread extends doubled through a loop of the second thread and around the doubled 75 first thread above the fabric. The loops of three threads are thus bound together around the edge of the fabric, forming a finish or seam thereon, which is, so far as I am aware, new in the art, and will form the subject of a 80 separate application.

It is of course understood that if desired the usual or any approved forms of tension and take-up devices may be applied to any one or more of the threads and that the work-plate can be provided with the usual finger to support the edge of the fabric and to receive the stitches when no fabric is present.

Having thus described my invention, what I claim as new is—

1. In an overseaming-machine such as described, the combination of a reciprocating thread-carrying needle, and two reciprocating thread-carrying loopers, one of said loopers moving in a path transverse to the axis 95 of the needle, to enter the loop of needle-thread below the fabric, and the other looper moving transversely to the first-named looper's line of motion, to enter the loop of thread carried by the said first-named looper and 100 deliver its loop in position beneath the needle to be entered thereby as it penetrates the fabric.

2. In an overseaming-machine such as described the combination of the vertically-reciprocating thread-carrying needle, the work-plate, a thread-carrying looper reciprocating horizontally beneath the work-plate in proximity to the needle when below the work-plate, to enter the loop of needle-thread, and 105 a thread-carrying looper reciprocating vertically and horizontally in proximity to the paths of the first-named looper and the needle, to enter the loop of thread carried by said first-named looper below the work-plate 110 and carry its thread above the work-plate in position to be entered by the needle; substantially as described, whereby a loop of second thread will be carried through the loop of needle-thread, and a loop of third 115 thread through the loop of second thread, said third-thread loop being confined by a second loop of needle-thread passing through it and the fabric.

3. In an overseaming-machine such as described, the combination of the work-plate, the reciprocating thread-carrying needle, a thread-carrying looper reciprocating around or over the edge of the work-plate in a plane substantially parallel with the needle's path, and a horizontally-reciprocating thread-carrying looper moving below the work-plate in a path diagonal to the plane of the first-named looper's motion and extending from

a point in rear of the needle to a point in front of the first-named looper; substantially as described.

4. In an overseaming-machine such as described, the combination of the work-plate; the vertically-reciprocating thread-carrying needle; the thread-carrying looper 1, provided with an entering-point, thread-guides, and a recess 12, said looper reciprocating horizontally beneath the work-plate; and the

thread-carrying looper 9 provided with an entering-point, an eye and a recess 14, said looper reciprocating around the edge of the work-plate from a point below looper 1 to a point above the work-plate beneath the 15 needle.

JOHN T. COLLINS.
